(57) **CLAIM**

The ornamental design for a tire for automobile as shown and described.

DESCRIPTION

1. Tire for automobile

1.1 : Front

1.2 : Enlarged

1.3 : Enlarged

1.4 : Enlarged

1.5 : End face view

1.6 : End face view

1.7 : Back

1.8 : Top

1.9 : Bottom

1.10 : Right

1.11 : Left

The broken lines shown in the drawings represent portions of a tire for automobile that form no part of the claimed design; fig. 1.1 is a front elevation view of the tire for automobile; fig. 1.2 is a partial enlarged view of A-B portion of fig. 1.1; fig. 1.3 is a partial enlarged view of C-D portion of fig. 1.2; fig. 1.4 is a partial enlarged view of E-F portion of fig. 1.1; fig. 1.5 is an end face view taken along line G-G of fig. 1.3; fig. 1.6 is an end face view taken along line H-H of fig. 1.4; fig. 1.7 is a back elevation view thereof; fig. 1.8 is a top plan view thereof; fig. 1.9 is a bottom plan view thereof; fig. 1.10 is a right side elevation view thereof; and fig. 1.11 is a left side elevation view thereof.
